DRY CLEANING COMPOSITIONS

John P. Miller III, Bloomfield, N.J., assignor to General Aniline & Film Corporation, New York, N.Y., a corporation of Delaware

No Drawing. Filed Jan. 4, 1957, Ser. No. 632,415

15 Claims. (Cl. 252—152)

This invention relates to improvements in the dry cleaning of fibrous textiles and related materials and more particularly to new and improved compositions for use with dry cleaning solvents, and to processes of dry cleaning wherein said improved compositions are employed.

It is well known that many types of fabrics and materials cannot be cleaned by the ordinary means of soap or detergents and water, such as are employed in laundering type operations since the presence of water deterioriously affects such materials. To provide effective cleaning for such materials, a dry cleaning process must be used. Dry cleaning processes employ organic solvents which are effective in removing from the materials treated most of the undesirable dirt, grease, dust and the like. It is also a common expedient in dry cleaning processes to add a small amount of water which, sufficiently dispersed in the dry cleaning fluid, will be effective to remove water-soluble stains without adversely affecting the material treated.

It is therefore an object of this invention to provide new compositions, particularly suitable for use in dry cleaning operations.

It is a further object of this invention to provide new compositions suitable for use in chlorinated dry cleaning solvents.

It is a still further object of this invention to provide new compositions which give outstanding and improved cleaning ability by virtue of an outstanding detergency action coupled with an excellent ability to prevent soil redeposition on the materials treated.

It is another object of this invention to provide an improved process of dry cleaning in chlorinated dry cleaning solvents.

It is a further object of this invention to provide an improved process of dry cleaning wherein chlorinated dry cleaning solvents are employed in conjunction with minor amounts of water.

According to the present invention the new compositions thereof, hereinafter termed dry cleaning compositions, to be incorporated in the chlorinated dry cleaning solvents contain as the essential components thereof a cationic surfactant derived from fatty amines and an alkylene oxide and a mixture of a nonionic and an anionic surfactant.

Compositions as above described give particularly outstanding results in chlorinated dry cleaning solvents. In addition, they give excellent results where a small amount of water has been incorporated into the dry cleaning solvent for the purposes described above. Among the chlorinated dry cleaning solvents one may use and which are normally employed in dry cleaning operations are the following:

Trichloroethylene
Tetrachloroethylene
Carbon tetrachloride, and the like

2

The cationic agents which are contemplated in this invention are derived, as described above, from fatty amines reacted with alkylene oxides or their equivalent. The fatty amines which are employed herein are those amines which contain at least 75% unsaturated linkages therein, of which at least 35% are of the double unsaturation type. Since such amines are usually obtained from natural fatty oils, they are usually employed as mixtures which mixtures correspond to the composition of the naturally occurring oils. Thus, an outstanding and preferred amine identifiable as a soybean amine is derived from the soybean oil fatty acids by ammonolysis and reduction to give a mixture of amines of the following approximate composition:

	Percent
Octadecadienyl amine	45
Octadecenyl amine	35
Octadecyl amine	10
Hexadecyl amine	10

It will be noted that this mixture contains 80% unsaturates of which 45% are of the diethenoid type. It is of course possible to employ in the preparation of the compositions of this invention synthetically prepared mixtures from the various amines within the scope of this invention and it is further possible to employ the pure unsaturated amines provided they come within the scope of the above limitations. In addition to soybean amine, numerous other fatty oils are suitable as precursors for the amines operable in this invention. Such fatty oils include cottonseed oil, corn oil, sesame oil, sunflower seed oil and the like. The approximate acid constituents of these oils are given below:

	Percent
Linoleic acid	51
Oleic acid	24
Saturated acids	25

	Percent
Linoleic acid	39
Oleic acid	43
Saturated acids and neutral materials	Remainder

	Percent
Linoleic acid	35
Oleic acid	46
Saturated acids and neutral materials	Remainder

	Percent
Linoleic acid	57
Oleic acid	33
Saturated acids and neutral materials	Remainder

Amines derived from these oils in the manner of that described above for soybean amine will contain at least 75% of the amine constituent as unsaturates of which amount at least 35% will represent doubly unsaturated compounds. In addition to the above mentioned fatty oils it is also possible to employ other naturally occurring materials which, upon suitable treatment by hydrolysis, ammonolysis and reduction, yield an amine or mixtures of amines coming within the scope of the limitations described above as to the unsaturation content thereof. The cationic agent suitable for use in the compositions of this invention are prepared from the above described amines or mixtures of amines by well known reactions with alkylene oxides or their equivalents.

The polyoxyalkylated products resulting from such processes which are suitable for use in this invention are those products which contain from about 14 to about 53% alkylene oxide (1 to 7 moles of alkylene oxide per mole of amine) or its equivalent. Methods for the preparation of such condensation products are described in U.S. Patents 1,970,578 and 2,213,477. The nonionic surfactants which are contemplated for use in the pres-

ent invention, as a second essential ingredient thereof, are those characterized as alkyl aryl polyoxyalkylene glycols. These glycol ethers may be derived in the known manner from alkylated aromatic hydroxy compounds of the benzene and naphthalene series such as p-n-butylphenol, amylcresol, diisobutylphenol, diamylphenol, isohexylphenol, oleylphenol, isododecylphenol, tetradecylphenol, isoocetylresorcinol, nonylphenol, dinonylphenol, isoocetylphenol, isoocetyl- β -naphthol, isohoxylxylenol, n-octadecylphenol, and the like. In general, these alkylated aromatic hydroxy compounds should contain at least one alkyl radical of at least 4 carbon atoms as a ring substituent. It will be understood that such compounds may contain up to 3 alkyl substituents which may be straight or branched, which substituents may contain a total of 20 or more carbon atoms.

These alkylarylhdroxy compounds are polyoxyalkylenated by reaction under proper conditions, preferably in the presence of an alkaline catalyst such as potassium hydroxide or sodium hydroxide, and heat and pressure, with from 3 to 7 moles of an alkylene oxide such as ethylene oxide, propylene oxide, or the like, or mixtures thereof.

The anionic surfactants to be employed as the third essential ingredient of the compositions of this invention comprise the anionic salts derived from the above-mentioned nonionic glycols. These anionic salts are readily prepared from said nonionic compounds by subjecting the glycol ether to esterification with a strong acid such as chlorosulfonic, sulfamic, sulfuric, or phosphoric or with an inorganic acid anhydride such as sulfur trioxide or phosphorus pentoxide or with acid halides such as sulfonyl chloride, phosphorus oxychloride or phosphorus pentachloride and the like. When a properly substituted acid mixture is employed in the esterification such as aminosulfonic acids, sulfamic acid, ammonium bisulfate, and the like, a water-soluble or dispersible salt is directly produced without the necessity of subsequent neutralization with a basic substance. In such cases, subsequent treatment with basic materials is only for the purpose of neutralizing excess acid, and the like. Excellent results are also obtained when complexes of some of the above acids and anhydrides are employed. For example, a combination of sulfur trioxide or chlorosulfonic acid with an ether such as dioxane, thioxane or β, β' -dichlorodiethylether, or with a tertiary nitrogen base such as pyridine or triethylamine may be used. The resulting esters may be neutralized with a basic material such as sodium hydroxide, potassium hydroxide, sodium carbonate, sodium acetate, ammonium hydroxide, ammonia, calcium oxide and hydroxide, magnesium oxide and hydroxide, strontium hydroxide, ethanolamine, diethanolamine, triethanolamine, methylamine, dimethylamine, trimethylamine, ethylamine, triethylamine, diethylamine, butylamine, propylamine, cyclohexylamine, morpholine, pyridine, octanamine, octylamine, and the like.

The greatest values to be derived from this invention lie not only in the superior detergent action of the dry cleaning compositions thereof but further, in the outstanding characteristics of soil redeposition prevention and whiteness retention which are evident in chlorinated dry cleaning solvents. In order to achieve the excellent and superior effects to be derived from the use of the compositions of this invention, the proportions of the various ingredients thereof must be employed within certain critical limits. The cationic surfactant which, as described above, is of the polyoxyalkylated-unsaturated-amine type, should comprise at least 15% on a volume basis of the total surfactants present, and no more than about 50%. The above described anionic agents should be employed within the range of 8.5 to 50% on a volume basis based on the total surfactants present. The nonionic compounds should be employed in amounts

4
5 on a volume basis of from 35 to 76.5% based on the total amount of surfactants present. The formulations hereinafter described where specific data is indicated for detergency action and whiteness retention characteristics were tested as follows:

6
7 Into each of 8 pint Mason jars there were introduced—

8
9 50 $\frac{1}{2}$ in. steel balls

10 50 ml. of solvent

11 1 $\frac{3}{2}$ in. diameter circular swatch of acetate jersey or Botany wool flannel, soiled or unsoiled, as indicated below:

12 The 8 jars contained the following:

13 15

TABLE I

Jar No.	Launder-Ometer Test Components	Test
1.	Acetate jersey soiled swatch.....	detergency.
2.	Wool flannel soiled swatch.....	Do.
20.	Acetate jersey soiled swatch, detergent wet stock.	Do.
3.	Wool flannel soiled swatch, detergent wet stock.	Do.
4.	Unsoiled acetate jersey swatch, 5 mg. synthetic to dry soil.	redeposition.
5.	Unsoiled acetate wool flannel swatch, 5 mg. synthetic dry soil.	Do.
6.	Unsoiled acetate jersey swatch, 5 mg. synthetic to dry soil.	Do.
25.	Unsoiled acetate wool flannel swatch, 5 mg. synthetic dry soil, detergent wet stock.	Do.
7.	Unsoiled acetate jersey swatch, 5 mg. synthetic dry soil, detergent wet stock.	Do.
8.	Unsoiled wool flannel swatch, 5 mg. synthetic dry soil, detergent wet stock.	Do.

30 The synthetic dry soil used in the above tests has the following composition:

31 35

TABLE II
Synthetic soil composition

Ingredients mixed as follows:

Components	Percent	Grams
hyperhumus.....	34.65	346.4
cement—Alpha Type I.....	15.00	150.0
SiO ₂ (gel—200 mesh, Davidson).....	15.00	150.0
40. avery clay (Harris Clay Co.).....	15.00	150.0
gelatin (Keystone 431X).....	3.50	35.0
NaCl (C.P. grade).....	5.00	50.0
Fe ₂ O ₃ (C. K. Williams).....	0.25	2.4
Carbon Black (Mallacco).....	1.50	15.0

45 The above was mixed in a ball mill until heterogeneous. The oils listed below were melted and blended by hand into the powdered mixture. They were:

Components	Percent	Grams
50. stearic acid.....	1.6	16.0
oleic acid.....	1.6	16.0
palm oil fatty acid (Harsborn).....	3.2	32.0
lauryl alcohol.....	0.5	5.0
55. lanolin anhydride (Merck).....	1.0	10.0
1-octadecane (Conn. hard rubber).....	1.1	11.0
1-octadecene (Humphrey Wilkinson).....	1.1	11.0

1500 ml. H₂O were added. The mixture was ball milled for 16 hours and dried. The dried soil then was pulverized in a hammer mill to approximately 200 mesh.

60 The cloth used for detergency tests was soiled by padding in the Butterworth three-roll padder, giving 3 passes through a 5% suspension of the synthetic dry soil in Stoddard Solvent and air drying the cloth. All cloth was stored in a constant humidity chamber prior to use at a relative humidity of 50 to 63%.

65 The test conditions were as follows:

Apparatus employed: Atlas Launder-Ometer (42 r.p.m.) with water bath drain to avoid excess moisture

70 Temperature: Temperature maintained at room temperature

Medium: Stoddard Solvent or perchlorethylene—50 cc.

Cleaning cycle: 15 min.

Rinse cycle: 15 min., in 50 cc. clean solvent

Control: Appropriate solvent with no detergent added

In the following examples which will serve to exemplify the compositions and processes of this invention, it will be understood that such exemplification is not deemed to be limitative of the invention herein covered. In the said examples, parts indicates parts on a volume basis unless otherwise indicated.

EXAMPLE 1

A mixture of:

5 parts of a blend comprising the following ingredients:

5 parts alkyl aryl polyoxyethylene glycol,¹ with
3 parts of ammonium salt of the sulfuric acid ester
thereof and

1 part of a cationic surfactant prepared from refined soybean amine containing 33% ethylene oxide.

is prepared.

The composition of the amine precursor compounds is as follows:

	Percent
Octadecadienyl amine	45
Octadecenyl amine	35
Octadecyl amine	10
Hexadecyl amine	10
	25

In Table III which follows there is set forth the efficiency of this formulation and a comparison with other commercial formulations and with a control solvent containing no detergent.

EXAMPLE 2

A mixture of:

2 parts of a blend comprising the following ingredients:

5 parts alkyl aryl polyoxyethylene glycol,¹ with
3 parts of ammonium salt of the sulfuric acid ester
thereof

2 parts of a cationic surfactant prepared from refined soybean amine containing 33% ethylene oxide

2 parts Stoddard Solvent

is prepared.

The efficiency of this formulation is given in Table III below:

¹ Condensation product of dinonyl phenol (1 mole) with 7 moles of ethylene oxide.

In the foregoing table, column 1 indicates the detergent tested, column 2 the fabric, which is prepared for the detergency tests as described above. Column 3 lists the solvents employed, column 4, the detergency efficiency where one is employed, based on reflectance readings. The standard is taken as a magnesium oxide block=100. The unsoiled rayon and wool have varying degrees of whiteness and therefore the significant values are the differences appearing in columns 5 and 7. Thus the larger the value in column 5 the better is the cleaning action of the composition. The smaller the figure in column 7 the better is the composition for preventing soil redeposition. The figures in column 6(a) are the values obtained for unsoiled, untreated fabrics, those of column 6(b) the values for the same swatches put through a cleaning cycle as indicated in Table I for jars 5-8.

In the following Examples 3 through 14, the components which are employed are the same as the three components of Examples 1 and 2 except that the proportions used are varied in accordance with the values given in the tabulation appearing below. In each instance the detergency efficiency and whiteness retention characteristics are comparable to those obtained with the compositions of Examples 1 and 2.

TABLE IV

30	Example	A Cationic Agent, ¹ Percent	B Anionic Agent, ² Percent	C Nonionic Agent, ³ Percent	D Ratio C:B
3		45	10	45	9:2
4		15	8.5	76.5	9:1

⁴ The "cleaned" wool was not cleaned in this test.

⁵ These agents useful in PCE only.

but the cationic agents AA and AB are, respectively, soybean amine condensation products containing 14% ethylene oxide and 53% ethylene oxide. Again, the results obtained in the detergency tests and whiteness retention tests show these compositions to be comparable in these characteristics to the compositions described above.

(b) corn oil amine containing 33% ethylene oxide, and (c) sesame oil amine containing 53% ethylene oxide. The results in so far as detergency value and whiteness retention characteristics are concerned are equivalent to those obtained above.

TABLE V

Example	I		II	III	IV

24	0	30	35	35	1:1
25	15	0	51	34	1:1.5
26	0	15	51	34	1:1.5

¹ AA is a soybean amine-ethylene oxide condensate containing 14% ethylene oxide.

² AB is a soybean amino-ethylene oxide condensate containing 53% ethylene oxide.

³ Ammonium salt of the sulfuric ester of the nonionic agent of Ex. 1.

⁴ Dinonyl phenol-ethylene oxide condensate of Ex. 1.

In the following Examples 27 through 38, the anionic and nonionic surfactants employed are similar to those used in the previous examples. The cationic agents are (a) cottonseed amine containing 14% ethylene oxide,

¹ AC is cottonseed amine containing 14% ethylene oxide.

² AD is corn oil amine containing 33% ethylene oxide.

³ AE is sesame oil amine containing 53% ethylene oxide.

⁴ Ammonium salt of the sulfuric ester of the nonionic agent of Ex. 1.

⁵ Dinonyl phenol-ethylene oxide condensate of Ex. 1.

NOTE.—The values given in the table above refer to parts.

In the following Examples 39 through 93 set forth in Table VII, various compositions within the ambit of this invention are shown. These compositions exhibit excellent detergent and whiteness retention abilities. The figures given indicate parts.

This invention has been disclosed with respect to certain preferred embodiments. Various modifications and variations of these embodiments will become apparent to those skilled in the art, and it is to be understood that such modifications and variations are to be included within the spirit and purview of this application and the scope of the appended claims.

I claim:

1. A composition adapted for use in the dry cleaning of textile and fibrous materials in chlorinated hydrocarbon dry cleaning solvent consisting essentially of a surface active agent mixture for each 100 parts of which there are present at least 15 parts of a polyoxyalkylated fatty amine surface active agent containing from about 14% to about 53% alkylene oxide, the said amine containing at least 35% octadecadienyl amine and the balance of said mixture a mixture of an anionic and an alkyl aryl polyoxyalkylene glycol ether nonionic surface active agent, the components of said mixture being present in the ratio of from about 1:9 to 1.5:1, the anionic surface active agent being selected from the group consisting of the sulfate and phosphate esters of alkyl aryl polyoxyalkylene glycols.

2. A composition as set forth in claim 1 wherein the fatty amine surface active agent is a soybean amine containing 14% ethylene oxide.

3. A composition as set forth in claim 1 wherein the fatty amine surface active agent is a soybean amine containing 33% ethylene oxide.

4. A composition as set forth in claim 1 wherein the fatty amine surface active agent is a soybean amine containing 53% ethylene oxide.

5. A composition as set forth in claim 3 wherein the ratio of anionic to nonionic surface active agent is about 2:1.

6. A composition as set forth in claim 3 wherein the ratio of anionic to nonionic surface active agent is about 1:1.5.

7. A composition adapted for use in the dry cleaning of textile and fibrous materials in chlorinated hydrocarbon dry cleaning solvent consisting essentially of a surface active agent mixture for each 100 parts of which there are present at least 15 parts of a polyoxyalkylated fatty amine cationic surface active agent containing at least 35% octadecadienyl amine and containing from about 14% to about 53% alkylene oxide, from about 35 parts to about 76.5 parts of an alkyl aryl polyoxyalkylated glycol nonionic surface active agent and from about 8.5 parts to about 50 parts of a salt of an ester se-

lected from the group consisting of sulfate and phosphate esters of said nonionic surface active agent.

8. A composition as defined in claim 7 wherein the cationic surface active agent is a soybean amine containing about 33% ethylene oxide, the nonionic surface active agent is a glycol derived from dinonylphenyl condensed with about 7 moles of ethylene oxide and the anionic surface active agent is the ammonium salt of the sulfuric acid ester of said nonionic surface active agent.

9. A composition as defined in claim 7 wherein the cationic surface active agent is a soybean amine containing about 14% ethylene oxide.

10. A composition as defined in claim 7 wherein the cationic surface active agent is a soybean amine containing about 53% ethylene oxide.

11. A composition as defined in claim 7 wherein the cationic surface active agent is a cottonseed amine, the nonionic surface active agent is a glycol derived from nonylphenol condensed with about 5 moles of ethylene oxide and the anionic surface active agent is the ammonium salt of the sulfuric acid ester of said nonionic surface active agent.

12. A composition as defined in claim 7 wherein the cationic surface active agent is a corn oil amine, the nonionic surface active agent is a glycol derived from isooctyl phenol condensed with about 7 moles of ethylene oxide and the anionic surface active agent is the ammonium salt of the sulfuric acid ester of said nonionic surface active agent.

13. A composition as defined in claim 7 wherein the cationic surface active agent is a sesame oil amine, the nonionic surface active agent is a glycol derived from nonylphenol condensed with about 3 moles of ethylene oxide and the anionic surface active agent is the ammonium salt of the sulfuric acid ester of said nonionic surface active agent.

14. A composition as defined in claim 8 wherein the cationic, anionic and nonionic surface active agents are in the ratio of about 3:2:1.

15. A composition as defined in claim 8 wherein the cationic, anionic and nonionic surface active agents are in the ratio of about 2:0.75:1.25.
